(57) **CLAIM**

The ornamental design for a transport wheelchair cover, as shown and described.

DESCRIPTION

FIG. 1 is a perspective view of a transport wheelchair cover, showing my new design in use;

FIG. 2 is a Front view thereof;

FIG. 3 is a Back view thereof;

FIG. 4 is a Left side view thereof;

FIG. 5 is a Right side view thereof;

FIG. 6 is a Top view thereof;

FIG. 7 is a Bottom view thereof; and,

FIG. 8 is a perspective view thereof; affixed to a transport wheelchair.

The broken lines are for environmental purposes only and form no parts of the claimed design.
